UNITED STATES PATENT OFFICE

FREDERICK W. WINKLER AND LOUIS L. KAESZ, OF JAMAICA, NEW YORK; SAID
WINKLER ASSIGNOR TO SAID KAESZ

DIRECTION FINDER

Application filed March 14, 1928. Serial No. 261,566.

This invention is a new direction finder (preferably including an improved magnetic compass) adapted for use on air or water craft, and comprises a stationary coil antenna 5 mounted at right angles to the center line of the air or water craft, a swinging coil antenna, means for oscillating the swinging coil antenna, and means operable through said antennæ for giving indications of electro-magnetic waves. These means may be an ordinary radio receiving instrument with a telephone capable of attachment to the head, and common to both antennæ and comprise a controlling device such as a switch for connecting 10 the swinging coil antenna and the stationary coil antenna alternately to a single radio receiving instrument. The improved magnetic compass may be of a standard form but it is provided with a movable indicating device.

In the accompanying drawings which illustrate an aeroplane embodying one form of this invention:

Fig. 1 is a side view partly in longitudinal section of an aeroplane embodying the invention;

Fig. 2 is a diagrammatic view showing certain parts, most of them in top view but some in side view;

Fig. 3 is a side elevation partly in section of the principal parts embodying the invention;

Fig. 4 is a front view of the dash board and a radio compass;

Fig. 5 is a top or face view of a magnetic compass with an appurtenance;

Fig. 6 is a top or face view of the appurtenance;

Fig. 7 is an edge view of the appurtenance 40 shown in Fig. 6;

Fig. 8 is a front view of a part shown in Fig. 4;

Fig. 9 is a front view of another part shown in Fig. 4;

Fig. 10 is a diagrammatic view of parts of a radio receiving instrument.

Similar letters of reference designate corresponding parts in all these figures.

A designates the body of the aeroplane.

It may be of ordinary construction provided

with a propeller P, wings B¹ and B² on each side, stabilizing fins C¹ and C², an adjustable elevator D and a rudder E. On its under side it is provided with a running gear comprising wheels F and a tail skid G.

H designates the operator's seat and I designates the dash board.

In the body A and, as here shown, rearwards of the operator's seat, a stationary coil antenna J is secured by means of mountings j¹. It consists, as here shown, of a rectangular frame and a wire coil fastened to this frame.

K designates a swinging coil antenna here shown as having its frame provided with 65 journals k¹ affixed to clamps k² which support this antenna, fitting in bearings k³ affixed to the body A. This antenna consists of a frame here shown of rectangular form and a wire coil fastened to this frame.

Affixed to one of the journals k¹ is a pulley k⁴ around which passes an endless cable L which also passes around a guide pulley l¹ that is mounted rotatably on the floor of the body A. The cable L next passes around a 75 pulley l² which is affixed to a shaft n¹ mounted rotatably in the dash board I. Thence it passes around another guide pulley l¹ to the pulley k⁴ of the swinging antenna coil K.

Affixed to the shaft n¹ is a handle N, here shown as made in the form of a knob, serving as a means for rotating the shaft n¹ and its pulley l² to cause the endless cable L to oscillate the swinging antenna coil K.

O¹ is a ring-shaped plate which is arranged 85 on the dash board opposite the operator's seat and, as here shown, it surrounds and is loosely mounted on the shaft n¹, so that either it or said shaft may have independent motion. This plate is marked with ordinary compass indications and there are on the dash board coincident marks a¹. A set screw may serve to fasten it in position after adjustment and also constitutes a handle for turning it.

Next to this plate is a ring-shaped plate 95 O² which is affixed to the shaft n¹ or to the handle N so as to turn with the latter: It has two pointers marked Max. and Min. and is an indicator of the position of the swinging coil antenna.

Q is a magnetic compass which, as here shown, is supported by a bracket q^1 affixed to the floor of the body A in such a manner as to be stationary. It may be of a form 5 commonly used in aeroplanes. It is provided with the usual two pointers q diametrically opposite to each other and has arranged relatively to it a ring-shaped piece q^2 constructed of resilient material and so as to have a tendency 10 to expand circumferentially. Its ends may be overlapped. It is provided with a pointer q^3 and preferably with a handle q^4 . It may be fitted in a recess provided in the upper part of the compass Q and retained 15 there by its resilience.

R designates a radio receiving instrument which may be of any ordinary form and which, as here shown, is electrically connected with a switch signal responsive device such 20 as an indicator consisting of head phone S.

The stationary antenna coil J is connected by wires j^2 with the radio receiving instrument and the swinging coil antenna K is connected by wires k^5 with the radio receiving 25 instrument.

The radio receiving instrument R is provided with a switch r^1 more particularly shown in Fig. 10.

Before describing the operation of the 30 various parts, it is important to explain that the same combination of parts in substantially the same arrangement will be applicable to all navigable vessels, even marine vessels.

The operator of a craft desiring to travel 35 towards any point adjusts the radio receiving instrument to the known wave band of a radio broadcasting station located at that point. Then he moves the switch r^1 to connect the swinging coil antenna K with the 40 radio receiving instrument R. Afterwards he oscillates this antenna by means of the handle N until the maximum intensity of radio impulses is attained. The attainment of this result can best be ascertained by an 45 indicator, which is supplementary to the radio receiving instrument, and the head phone S is a useful form of such an indicator. Next the operator turns the movable compass 50 card O^1 so that course marks learned from the magnetic compass will align with marks a^1 upon the dash-board shown in Fig. 4.

When maximum intensity has been attained, the ring-shaped plate O^2 will indicate the general direction of the course 55 through the pointer marked Max. and the swinging coil antenna K will point to general direction of the broadcasting station. If now the craft is maneuvered until its longitudinal axis coincides with said position of the 60 swinging coil antenna both the craft and this antenna will point towards the broadcasting station.

Due to the fact that the maximum intensity of signal reception is not by the swinging 65 coil antenna very sharply defined it is

necessary to further rotate this antenna to a point where minimum or no signal will be heard. This point will be indicated by indicating mark Min. of the plate O^2 relative to the plate O^1 . This resulting indication will be the exact course direction with respect to the magnetic compass. The pointer q^3 of the ring-shaped pieces q^2 is then set on the magnetic compass to correspond with the direction found by the indicating mark Min. of the indicator O^2 . The craft is then maneuvered in the direction of its course and the swinging coil antenna readjusted so that it is aligned with the axis of the ship whereupon both the craft and this antenna will point towards its destination. 70

If the switch r^1 is now moved to disconnect the swinging coil antenna K from the radio receiving instrument R and to connect to the latter the stationary coil antenna J, this antenna should be used to verify what has been learned from the swinging coil antenna because while the craft is pointing towards the broadcasting station no indication of the station will be obtainable through the stationary coil antenna. 80

When the swinging antenna has been adjusted to attain the maximum radio indications the pointer marked Max. of the ring-shaped plate O^2 will show the course. Then the ring-shaped plate O^1 marked with compass indications is turned to correspond to the position indicated by the magnetic compass. 90

To find a location with reference to longitude and latitude the ring-shaped plate O^1 is turned to correspond with the magnetic compass and then fastened in position. Then the indicator O^2 and swinging coil antenna K are turned to find a desired broadcasting station of known location. When this is 100 found, the angle with reference to the north line as indicated in the magnetic compass is noted. Next the direction line is marked upon the chart at a position where it will intersect with a north and south line of the chart. The angle of these two lines is then measured and this may be easily done by use of a protractor. The point of intersection of the two lines will be the location of the 105 craft. 110

To check the location so ascertained another broadcasting station of known location will be found. This will preferably be at a considerable distance from the one first used. After finding the second broadcasting station, the procedure will be the same as that already described for the first. 115

What is claimed and desired to be secured by Letters Patent is:—

1. In a craft, the combination, with two directional antenna, one fixed in such relation relative to the craft as to give a minimum signal current when the craft is headed for the radio beacon at a desired destination, the second antenna being so mounted as to be 125 130

capable of angular movement from a position to give a current of maximum signal strength, to a position to give a current of minimum signal strength, in response to signals from said beacon, irrespective of the direction of travel of the craft; indicating means actuated by the swinging of said second antenna for determining the angular relation between the line of propulsion of the craft and the bearing of the destination beacon as given by the position of the second antenna at a predetermined signal current, a radio receiver, signal responsive mechanism connected to said receiver, and switch mechanism for alternatively closing either antenna onto the radio receiver and simultaneously opening the circuit of the other antenna.

2. In a craft, a rotatable directional antenna; a stationary directional antenna mounted perpendicularly to the line of propulsion of said craft; a radio receiver when connected to either antenna responsive to signals received through said connected antenna; bearing indicator means cooperating with said rotatable antenna to determine the direction of the source of said signals and means for connecting said receiver with either antenna to make it responsive to signals received through said connected antenna.

3. In a craft, a rotatable directional antenna; a stationary directional antenna mounted perpendicularly to the line of propulsion of said craft; a radio receiver responsive to signals received through said rotatable antenna; bearing indicator means cooperating with said rotatable antenna to determine the direction of the source of said signals and means for thereafter rendering said receiver responsive to said same signals received through said stationary antenna for continually indicating the direction of said craft.

Signed at New York in the county of New York and State of New York this 12th day of March A. D. 1928.
